UNITED STATES PATENT OFFICE.

WILLIAM C. A. EBERHARDT, OF RACINE, WISCONSIN.

HEAT-DISTRIBUTUTING DEVICE.

1,276,886.

Specification of Letters Patent. Patented Aug. 27, 1918.

Application filed December 4, 1916. Serial No. 134,850.

To all whom it may concern:

Be it known that I, WILLIAM C. A. EBERHARDT, a citizen of the United States, residing at 1664 N. Wisconsin street, Racine, in the county of Racine and State of Wisconsin, have invented a new and useful Heat-Distributing Device, of which the following is a specification.

My invention relates to heat-distributing devices, especially designed to be used in connection with portable oil heaters or similar heaters. The object is to distribute the heat generated by the heater in such a manner as to obtain the most possible benefit of it.

Further objects and advantages of my invention will hereinafter be described, reference being had to the accompanying drawing, illustrating my invention, and forming a part of this specification, and where Figure 1 is a sectional view of the device taken through the center, on the line 1—1 Fig. 2, Fig. 1 also shows the practical application of my invention, being set over the top part of an oil heater, and supported on top of it by brackets. Fig. 2 is a plan view thereof, the cover designated by the numeral 5 being removed, and the bladed disk designated by the numeral 4 shown in full. Fig. 3 is a plan view of the body proper separate, consisting of the parts designated by the numerals 1, 2 and 3. The supporting brackets designated by the numeral 6 are also shown in this view. Fig. 4 is a plan view of the perforated cover designated by the numeral 5.

In the drawing wherein is illustrated a preferred embodiment of my invention, the numeral 1 designates the upper portion of the outer wall of the body, being vertically disposed and circular in horizontal cross section; the numeral 2 designates the lower portion of the outer wall of the body, which is coneshaped and is perforated all around near its lower edge, and is substantially attached to portion 1; the numeral 3 designates the inner wall of the body and which is also vertically disposed and circular in horizontal cross section and is substantially attached to portion 2 of the outer wall at its lower edge. The numeral 4 designates a bladed disk, the blades being radially disposed and turned to stand at an angle in relation to the central and horizontally disposed

portion. The bladed disk is suspended from cover above by means of a screw or similar means designated by the numeral 10, Fig. 1. The numeral 5 designates a cover, a plan view of which is shown in Fig. 4, being perforated to permit the heat generated by the heater to pass through. The object of the cover is to hide from the eye the less ornamental parts of the device. The numeral 6 designates supporting brackets which are three in number and are designed to fit the various sizes of heaters, and are mounted on the inside of outer wall by any suitable means. The numeral 8 designates the heater, which is not a part of the invention. The numeral 9 designates the perforations in the part designated by the numeral 2. The numeral 10 designates a screw or bolt used to suspend bladed disk 4 from perforated cover 5. The numeral 11 designates the perforations in the perforated cover, designated by the numeral 5.

In the use of my invention, the same is set over the top of a heater in the manner shown on the drawing, and is supported by the supporting brackets on top of heater. The heat generated by the heater, rising, strikes the bladed disk, spreads, heating the blades to their full extent passes off through the spaces between the blades, causing a circulation of air through the spaces formed by the outer and inner wall of the body of the device through the perforations near the lower edge, and by the inner wall of the device body and the heater, traveling upward, striking the heated bladed disk, mingling with the heat, passing off through the spaces between the blades, sweeping same and then passing off through the perforated cover into the room, thus taking the cold air from the floor, circulating it through the device and giving it off at the top in large volumes uniformly heated and distributed in a most effective manner.

Having fully described my invention, I claim:

1. A heat distributing device of the kind described, comprising a cylindrical casing, having a perforated cone-shaped lower portion, and an inner open ended cylinder shorter than said casing and with its lower end joined to the lower end of the cone shaped portion, and a bladed disk mounted in said casing above said cylinder, said disk

having a flat central portion with blades extending radially therefrom and located at an angle to the upper end of said cylinder.

2. A heat distributing device of the kind described, comprising a cylindrical casing having an inwardly inclined perforated lower portion, and an inner open ended cylinder, shorter than the outer casing, and

spaced therefrom, and joined at its lower end to the lower end of the outer casing, a bladed disk mounted within the outer casing and above said cylinder, a perforated cover on the casing, and brackets on the casing adapting it to be mounted on a heater.

In testimony whereof I affix my signature. 15

WILLIAM C. A. EBERHARDT.
